CLAIM

The ornamental design for a blockshelf, as shown and described.

DESCRIPTION

FIG. 1 is an isometric view of a blockshelf, showing my new design;

FIG. 2 is an exploded isometric view thereof;

FIG. 3 is the end view thereof;

FIG. 4 is the front view thereof;

FIG. 5 is a bottom view thereof;

FIG. 6 is a top plan view thereof;

FIG. 7 is a cross-section view of FIG. 3 thereof;

FIG. 8 is a cross-section view of FIG. 4 thereof;

FIG. 9 is an exploded view of FIG. 8 thereof;

FIG. 10 is an exploded plan section thereof;

FIG. 11 is a side elevation view thereof shown with environment;

FIG. 12 is a front elevation view thereof shown with environment;

FIG. 13 is an exploded view shown with environment; and, FIG. 14 is an isometric view shown with environment thereof.

The stippled technique represents shading.

The broken lines depict environmental subject matter only and form no part of the claimed design.
